Application December 9, 1954, Serial No. 474,176

Claims priority, application Germany December 30, 1953

8 Claims. (Cl. 315—347)

The present invention relates to electric discharge lamps and more particularly to high pressure gaseous discharge lamps in which starting of such lamps at the available line voltage is facilitated by the generation of a magnetic field.

It is well known in the discharge lamp art to employ a magnetic field generated by either a permanent or electromagnet disposed exteriorly of the lamp envelope to stabilize the arc discharge, or to shift the latter from its otherwise normal position. In some instances it has also been proposed to employ the conductors for the lamp electrodes for the generation of a magnetic field, to accomplish the same purpose as the exteriorly positioned permanent or electromagnets.

The present invention likewise contemplates the generation of a magnetic field by the leading-in and supporting conductors but the primary object of using such magnetic field is to facilitate starting of the lamp after which such field performs its previously known purpose of stabilizing the discharge or shifting it to a desired position within the lamp envelope. The utilization of a magnetic field to facilitate starting has been found to be particularly desirable with gaseous discharge lamps having a krypton and/or xenon filling at a pressure of several atmospheres, even as high as one hundred atmospheres, because owing to the low potential gradient of the ensuing high-pressure gaseous discharge the operating current intensities and in consequence thereof the magnetic field produced by a simple leading-in and supporting conductor is of considerable magnitude.

Discharge lamps of this type are accordingly provided by the present invention in which the arc discharge is influenced by a magnetic field generated by the leading-in and supporting conductors for the spaced electrodes within the lamp envelope. In addition, such leading-in and supporting conductors are provided with a small section spaced in close proximity to each other for the purpose of initiating a discharge at such section upon the application of line voltage to the lamp, while the remainder of such leading-in and supporting conductors are spaced apart a distance sufficient to prevent the formation of a discharge therebetween particularly when it is borne in mind that such leading-in and supporting conductors are constructed of a material, coated or covered, so as to not be electron emissive and thus not conducive of the formation of a cathode spot. Also, these leading-in and supporting conductors are so disposed within the lamp envelope that the magnetic field generated thereby relative to the direction of current flow, upon initiation of an arc discharge between the closely spaced sections of the leading-in and supporting conductors, causes such arc discharge to travel or be transposed along the conductors to the spaced electron emissive electrodes where such arc discharge remains during operation of said lamp.

By providing the leading-in and supporting conductors with the section spaced in close proximity to each other, or as a modification interposing a starting electrode therebetween, the required starting voltage is propor-

2

tionately low. This is important especially since it is recognized that with high-pressure gaseous discharge lamps generally the starting voltage is very high due to the high pressure existing in such lamps even under cold non-operating conditions and that this starting voltage becomes higher with an increase in the spacing across which the arc discharge path must travel. By means of the particular shape of the leading-in and supporting conductors provided by the present invention, the arc, as previously mentioned, does not remain at the closely spaced section of the conductors or between the starting electrode and a conductor where it is first initiated but such arc is forced to travel along the leading-in and supporting conductors to the most distantly spaced ends thereof which serve as the electrodes or are specifically provided with electron emissive electrodes.

Also, as previously mentioned, it is essential that appropriate steps be taken to eliminate the possibility of the arc discharge remaining at the section of the conductors in close proximity to each other where it is initiated. Such steps accordingly comprise the selection of a material for the leading-in conductors, such as the highly refractory metals of tungsten or tantalum, as well as zirconium, and making them of sufficient cross-section that heat is readily dissipated so that a cathode spot cannot be formed or by coating or covering the leading-in and supporting conductors with a suitable non-emissive material. It is also highly desirable that the small sections of the leading-in and supporting conductors in close proximity to each other, or the starting electrode if employed, where the discharge is initiated, be positioned to one side of the discharge path between the electrodes or below the operating electrodes. In this manner the convection currents arising from initiation of the arc discharge will assist the traveling of the arc from its place of origin to the operating electrodes and preclude any tendency for the arc to travel in an opposite direction, since it must accordingly travel either vertically or horizontally. In the event of proportionately low operating current intensity the magnetic field produced by the leading-in and supporting conductors is too weak to definitely assure the transposition of the arc discharge from the section where it is initiated to the operating electrodes, then such current intensity may be suitably increased even to a value higher than the final operating current intensity and maintained at such increased value until the arc discharge has completed its travel from the point of origin to the operating electrodes.

The present invention in one of its modifications also eliminates the necessity for an external starting switch by providing a switching arrangement operable entirely automatically and positioned within the lamp envelope. For example, one of the leading-in and supporting conductors carrying a first operating electrode at its end is provided with the aforementioned small section in close proximity to the other leading-in conductor which section is not too distant from the first operating electrode. The second leading-in and supporting conductor, which carries the second operating electrode at its end and spaced a substantial distance from the first operating electrode, serves as an auxiliary electrode relative to that section of the first leading-in and supporting conductor employed for initiating the arc discharge. Since the second operating electrode is not electrically connected with the second leading-in and supporting conductor, the arc discharge is thus initiated between the leading-in and supporting conductor for the first operating electrode and this auxiliary electrode and then travels to the first operating electrode until it flashes over to the second operating electrode which has a special electric current leading-in conductor. Transfer of the discharge from between the first operating electrode and the auxiliary electrode

over to between the two operating electrodes is also facilitated if the second operating electrode is at a slightly higher potential than that applied to the auxiliary electrode. From the foregoing it thus becomes readily apparent that not only is an external starting switch eliminated for starting the lamp but the internal switching over of the arc discharge can be utilized if desired to automatically connect an additional external magnetic field generator into the arrangement.

The foregoing description of the present invention may be better appreciated by reference to the accompanying drawings showing various embodiments of the invention wherein:

Figure 1 shows a cross-sectional view of a high-pressure gaseous discharge lamp of the present invention designed particularly for vertical operation,

Fig. 2 is a cross-sectional view taken on the line II—II of Fig. 1,

Fig. 3 is a cross-sectional view somewhat similar to Fig. 2 but showing a slight modification which the lamp of the present invention may take,

Fig. 4 shows another modification which the lamp of the present invention may take and designed more particularly for horizontal operation,

Fig. 5 is a longer arc-discharge lamp of the present invention and thus an additional modification thereof,

Fig. 6 is a cross-sectional view taken on the line VI—VI of Fig. 5,

Fig. 7 is a side view of another modification of a horizontal operating lamp made in accordance with the present invention,

Fig. 8 is a sectional view showing the position of the pole shoes of Fig. 7 relative to the lamp and the ensuing arc discharge,

Fig. 9 is a still further modification of a lamp designed in accordance with the present invention for horizontal operation.

Referring now to the drawing in detail, the high-pressure gaseous discharge lamp as shown in Fig. 1 comprises an envelope 1 of quartz or similar high-melting point glass which is filled with krypton and/or xenon to a pressure of about 3 to 10 atmospheres at ambient temperature. The leading-in wires 3, 4 and 5 are sealed vacuum tight through the stem 2. In the interior of the envelope 1 these leading-in wires are connected to supporting conductors carrying electrodes or themselves constituting electrodes. For example, the supporting conductor 6 is connected to leading-in wire 3 and its free inner end 7 serves as an operating electrode, while supporting conductor 8, with its free inner end 9 serving as another operating electrode 9, is connected to leading-in wire 5.

As shown in Fig. 1, the conductor 8 is provided with a small section 11 spaced in close proximity to a point 10 on conductor 6 compared with the much greater spacing between the electrodes 7 and 9. This short gap between the conductors 6 and 8 at the points 10 and 11 facilitates the initiation of a discharge with a proportionally low voltage but in addition an auxiliary electrode 12 connected to the leading-in wire 4 may be provided, if desired. Following initiation of the arc discharge between the points 10 and 11, with attendant current flow through the conductors 6 and 8, a magnetic field is generated by such conductors which causes the arc discharge to travel along these conductors 6 and 8 until it is transposed to the electrode ends 7 and 9 where the discharge remains during continued operation of the lamp. In this particular embodiment of the present invention the traveling of the arc discharge is facilitated by convection currents since the discharge is initiated below the operating electrodes causing the upward flow of convection currents. Moreover, the leading-in and supporting conductors 6 and 8 throughout their length, other than at the points 10 and 11, are spaced apart a distance sufficient to prevent the formation of a cathode spot and are of a

material, such as tungsten, tantalum or zirconium which is not conducive to the formation of a cathode spot at the available voltage, or if preferred the supporting conductors may be coated or covered with a non-electron emissive material.

It will also be noted from Fig. 1 that the conductors 6 and 8 are so positioned within the envelope 1 that the electrode ends 7 and 9 are disposed in a channel formed by a longitudinal recess 13 in the envelope wall, so that the ensuing discharge between these operating electrodes 7 and 9 will be more or less restricted to this channel recess 13 at one side of the lamp. Such restriction of the arc discharge likewise will restrict the blackening of the envelope by electrode deposits to this channel and perhaps to the top 14 of the envelope so that the remainder of the envelope wall being further away from this channel remains substantially free of deposits and hence radiation of light or, in a particular case, of invisible radiation will not be impaired during lamp life. To further protect the top of the envelope 14 from blackening a screen 15 may also be employed. In order to restrict envelope blackening it is not entirely essential to provide the envelope with the longitudinal recess 13 since an arcuate sleeve 16 extending longitudinally of the envelope 1, as shown in the modification of Fig. 3, will accomplish the same purpose.

In the case of high pressure gaseous discharge lamps primarily intended for horizontal operation of the arc discharge the present invention may be utilized in the manner shown in Fig. 4. Here again the supporting conductors 6 and 8 are shown with their points 10 and 11 in close proximity to each other for initiating the discharge in the same manner as above mentioned with respect to the embodiment shown in Fig. 1. Accordingly, the arc discharge will likewise travel under the influence of the magnetic field created by the conductors 6 and 8, or the leading-in wires 3 and 5, through which current is flowing along the leads until such discharge is transposed to the electrode ends 7 and 9 where it remains during continued operation of the lamp as above described. The repelling effect of the magnetic force to the conductor 6 and of the arc 17 will tend to suppress the convection effect which urges the highly heated and lighter arc gases in an upward direction. Thus by appropriate control it is possible to raise horizontal arc discharges upwardly several millimeters into a much stabler operating position than is possible with vertically operating arc discharges under the same circumstances.

A lamp is shown in the modification of Fig. 5 in which initiation and stabilization of a long arc discharge is obtained in accordance with the present invention, which has not heretofore been obtainable. This has been due to the fact that at the lower gradient and restriction of the arc length to but a few millimeters because of stability reasons, a high pressure gaseous discharge lamp with a rare gas filling would not allow voltage ranges above 30 to 40 volts without stabilization of the envelope wall. In Fig. 5 an upward directed force results from the effect of the magnetic field from conductor 6 on the arc between the electrodes 7 and 9 whereas the arc is also urged downwardly by the magnetic field created by the conductors 18 provided above the lamp, as shown more clearly in Fig. 6. Accordingly, the present invention provides a means for obtaining an equilibrium so that the arc will burn stably in the tube axis and an overloading of the upper zones of the lamp envelope is prevented or, conversely, a higher loading is possible than can be obtained with wall-stabilization.

As shown in Fig. 6 the parallel arranged conductors 18 are provided on a cylindrical jacket around the arc as axis. This arrangement of the conductors 18 is of importance for the purpose of preventing urging of the arc to one side of its true axis between the electrodes. A similar magnetic field may also be produced in the form of a channel by providing electromagnets 19 with elong-

gated pole pieces 20, as shown in Fig. 7. The coils 21 having a few windings through which lamp current flows will produce a uniform magnetic field corresponding to the arc length, as indicated by the arrows as shown in Fig. 7. Fig. 8 shows in a sectional view, the position of the pole pieces 20 relative to the lamp envelope 1 and the arc discharge 17 so that as little of the light flux of the arc is absorbed as possible.

Referring again to Fig. 5 the arc discharge is initiated between the points 10 and 11 of the conductors 6 and 8 as before explained but in this instance it is produced by the higher potential impressed across the auxiliary electrode 12. Such starting of the arc discharge may be also effected by opening a starting contact carried by a bimetallic strip or by a magnetically operable switch or should it be preferred the discharge may be started by application of a sufficiently high enough voltage directly across the main electrodes 7 and 9. Once started, the arc discharge at point 10 on conductor 6 (Fig. 5) is forced by the previously described magnetic field along the conductor 6 to its main electrode end 7. However, in order for the magnetic field of the conductors 6 and 8 to be effective, the opposing magnetic field created by the conductors 18 has to be removed by closing switch 22 and thus short-circuiting a portion of choke coil 23 which increases the current of the discharge and hence the internal magnetic field. It is also possible to utilize the magnetic field from the conductors 18 to assist the internal field in transposing the arc discharge from its point of origin to the operating electrodes 7 and 9, if desired, by providing a pole changing switch as can be readily understood.

It is also not absolutely essential to provide the special switch 22 for the outer magnetic field if, as shown in Fig. 9, the arc is first started between the current conductor of only one operating electrode and an auxiliary electrode from which it is subsequently transposed to the most distant operating electrode. This modification, as shown in Fig. 9, is for a horizontal operating lamp 1 which again is provided with the main operating electrodes 7 and 9, in this instance are carried by supporting conductors 11 and 25. Adjacent to the operating electrode 9 or to the supporting conductor 11 is the closely spaced section 10 of the conductor 6, the end of which constitutes an auxiliary electrode 24, and the additional starting electrode 12 may again be provided between the sections 10 and 11 as previously described relative to Fig. 5.

The arc discharge initiated between the sections 10 and 11 likewise travels, under the influence of the magnetic field created by the leading-in and supporting conductors 6 and 11, along the auxiliary electrode until it reaches the end thereof 24 from whence it flashes over to the operating electrode 7. For increasing the strength of the magnetic field generated by the conductors 6-10 and 11, the current intensity may be raised by the provision of a tap 26 connected to the choke coil 23. Also, a higher potential may be impressed across the operating electrodes 7 and 9 than between the main electrode 7 and the auxiliary electrode 24, by connecting the operating electrode 7 to the free end of the choke coil 23 since both winding sections 27 and 28 are then in circuit so that the entire choke 23 thus acts as a transformer increasing the potential above that produced by only the choke section 27 alone, to which the auxiliary electrode 24 is connected. Also, as soon as the arc discharge is transposed from the auxiliary electrode 24 to the operating electrode 7, the current intensity of the arc is automatically decreased because it is restricted by the full windings of the choke coil 23.

If, during operation, convection currents tend to cause a curvature in the arc discharge between the operating electrodes 7 and 9, it can be returned to a straight-line discharge in opposition to the force of the convection currents, by the application of an exterior magnetic field from the magnetic winding 18'. Such winding 18', being con-

nected in circuit with operating electrode 7, has no effect on the internal magnetic field created by the conductors 6-10 and 11 because this winding 18' is inoperative until the arc discharge is transposed to operating electrode 7 at which time such winding 18' only then becomes automatically operative.

From the foregoing it should thus become obvious to those skilled in the art that a high pressure gaseous discharge lamp has been provided by the foregoing in which a magnetic field is utilized to facilitate starting of such lamp at a low voltage. Moreover, such magnetic field is created by the positioning of the leading-in and supporting conductors which field is of sufficient magnitude as to cause the discharge, once it is initiated, to be very rapidly transposed to the main operating electrodes.

It is also to be understood that while several embodiments of the present invention have been shown and described, still further modifications thereof may be made without departing from the spirit and scope of the appended claims.

We claim:

1. An electric high-pressure gaseous discharge lamp comprising an envelope provided with spaced electron emissive electrodes therein between which a discharge 25 occurs during operation of said lamp, leading-in and electrode-supporting conductors within said envelope of less electron emissivity than said electrodes and having a small portion thereof in close proximity to each other to initiate a discharge upon the application of a voltage to said lamp between said closely spaced portions, with the remainder of said leading-in and supporting conductors spaced apart a distance sufficient to prevent the formation of a discharge therebetween; and said leading-in and electrode-supporting conductors being so positioned relative to each other that, upon initiation of the discharge with the attendant direction of current flow therethrough relative to the discharge, a magnetic field is generated between such leading-in and electrode-supporting conductors, which causes the discharge to be transposed from the closely spaced discharge initiating portion of said leading-in and electrode-supporting conductors, to the spaced electron emissive electrodes where the discharge remains during operation of said lamp.

2. An electric high-pressure gaseous discharge lamp 45 comprising an envelope having a base and provided with spaced electron emissive electrodes therein between which a discharge occurs during operation of said lamp, leading-in and electrode-supporting conductors within said envelope of less electron emissivity than said electrodes and 50 having a small portion thereof in close proximity to each other and located between said base and the most adjacent electrode to initiate a discharge upon the application of a voltage to said lamp between said closely spaced portions, with the remainder of said leading-in and supporting conductors spaced apart a distance sufficient to prevent the formation of a discharge therebetween; and said leading-in and electrode-supporting conductors being so positioned relative to each other that, upon initiation of the discharge with the attendant direction of current flow therethrough relative to the discharge, a magnetic field is generated between such leading-in and electrode-supporting conductors which causes the discharge to be transposed from the closely spaced discharge initiating portion of said leading-in and electrode-supporting conductors to the spaced electron emissive electrodes where the discharge remains during operation of said lamp.

3. An electric high-pressure gaseous discharge lamp comprising an envelope provided with spaced electron emissive electrodes therein between which a discharge occurs during operation of said lamp, leading-in and electrode-supporting conductors within said envelope of less electron emissivity than said electrodes and having a small portion thereof in close proximity to each other and located to one side of the discharge path between said 70 electrodes to initiate a discharge upon the application of

a voltage to said lamp between said closely spaced portions, with the remainder of said leading-in and supporting conductors spaced apart a distance sufficient to prevent the formation of a discharge therebetween; and said leading-in and electrode-supporting conductors being so positioned relative to each other that, upon initiation of the discharge with the attendant direction of current flow therethrough relative to the discharge, a magnetic field is generated between such leading-in and electrode-supporting conductors, which causes the discharge to be transposed from the closely spaced discharge initiating portion of said leading-in and electrode-supporting conductors, to the spaced electron emissive electrodes where the discharge remains during operation of said lamp.

4. An electric high-pressure gaseous discharge lamp comprising an envelope provided with spaced electron emissive electrodes therein between which a discharge occurs during operation of said lamp, leading-in and electrode-supporting conductors within said envelope of less electron emissivity than said electrodes and having a small portion thereof in close proximity to each other, a starting electrode adjacent said small closely spaced portion to initiate a discharge upon the application of a voltage to said lamp between said starting electrode and the closely spaced portion of one of said leading-in and electrode-supporting conductors, with the remainder of said leading-in and supporting conductors spaced apart a distance sufficient to prevent the formation of a discharge therebetween; and said leading-in and electrode-supporting conductors being so positioned relative to each other that, upon initiation of the discharge with the attendant direction of current flow therethrough relative to the discharge, a magnetic field is generated between such leading-in and electrode-supporting conductors, which causes the discharge to be transposed from the starting electrode and the adjacent closely spaced discharge initiating portion of said leading-in and electrode-supporting conductors, to the spaced electron emissive electrodes where the discharge remains during operation of said lamp.

5. An electric high-pressure gaseous discharge lamp comprising an envelope provided with spaced electron emissive electrodes thereon between which a discharge occurs during operation of said lamp, leading-in and electrode-supporting conductors within said envelope of less electron emissivity than said electrodes and having a small portion thereof in close proximity to each other, a deflectable starting electrode adjacent said small closely spaced portion to initiate a discharge upon the application of a voltage to said lamp between said deflectable starting electrode and the closely spaced portion of one of said leading-in and electrode supporting conductors, with the remainder of said leading-in and supporting conductors spaced apart a distance sufficient to prevent the formation of a discharge therebetween, and said leading-in and electrode-supporting conductors being so positioned relative to each other that, upon initiation of the discharge with the attendant direction of current flow therethrough relative to the discharge, a magnetic field is generated between such leading-in and electrode-supporting conductors, which causes the discharge to be transported from the deflectable starting electrode and the adjacent closely spaced discharge initiating portion of said leading-in and electrode-supporting conductors, to the spaced electron emissive electrodes where the discharge remains during operation of said lamp.

6. An electric high-pressure gaseous discharge lamp comprising an envelope provided with a longitudinal groove in the wall thereof, spaced electron emissive electrodes positioned adjacent each end of said groove between which a discharge occurs during operation of said lamp, leading-in and electrode-supporting conductors within said envelope of less electron emissivity than said electrodes and having a small portion thereof in close proximity to each other to initiate a discharge upon the

10
15

application of a voltage to said lamp between said closely spaced portions, with the remainder of said leading-in and supporting conductors spaced apart a distance sufficient to prevent the formation of a discharge therebetween, and said leading-in and electrode-supporting conductors being so positioned relative to each other that, upon initiation of the discharge with the attendant direction of current flow therethrough relative to the discharge, a magnetic field is generated between such leading-in and electrode-supporting conductors which causes the discharge to be transposed from the closely spaced discharge initiating portion of said leading-in and electrode-supporting conductors to the spaced electron emissive electrodes in said longitudinal groove where the discharge remains during operation of said lamp.

7. An electric high-pressure gaseous discharge lamp comprising an envelope provided with spaced electron emissive electrodes therein between which a discharge occurs during operation of said lamp, leading-in and electrode-supporting conductors within said envelope of less electron emissivity than said electrodes and having a small portion thereof in close proximity to each other to initiate a discharge upon the application of a voltage to said lamp between said closely spaced portions, with the remainder of said leading-in and supporting conductors spaced apart a distance sufficient to prevent the formation of a discharge therebetween, and said leading-in and electrode-supporting conductors being so positioned relative to each other that, upon initiation of the discharge with the attendant direction of current flow therethrough relative to the discharge, a magnetic field is generated between such leading-in and electrode-supporting conductors which causes the discharge to be transposed from the closely spaced discharge initiating portion of said leading-in and electrode-supporting conductors to the spaced electron emissive electrodes where the discharge remains during operation of said lamp, and means disposed exteriorly of said lamp for generating a magnetic field of opposite direction to the magnetic field generated by said interiorly disposed leading-in and electrode-supporting conductors, to cause stabilization of the discharge within said envelope between said magnetic fields.

8. An electric high-pressure gaseous discharge lamp comprising an envelope provided with spaced electron emissive electrodes therein between which a discharge occurs during operation of said lamp, leading-in and electrode-supporting conductors within said envelope of less electron emissivity than said electrodes and having a small portion thereof in close proximity to each other to initiate a discharge upon the application of a voltage to said lamp between said closely spaced portions, with the remainder of said leading-in and supporting conductors spaced apart a distance sufficient to prevent the formation of a discharge therebetween, and said leading-in and electrode-supporting conductors being so positioned relative to each other that, upon initiation of the discharge with the attendant direction of current flow therethrough relative to the discharge, a magnetic field is generated between such leading-in and electrode-supporting conductors which causes the discharge to be transposed from the closely spaced discharge initiating portion of said leading-in and electrode-supporting conductors to the spaced electron emissive electrodes where the discharge remains during operation of said lamp, and magnetic-field-producing conductors extending longitudinally of the envelope exterior and in an arcuate plane partially about said envelope for generating a magnetic field with the ensuing arc discharge within said envelope as the axis for the arcuately disposed magnetic-field producing exterior conductors.
